UNITED STATES PATENT OFFICE.

EDWARD P. CALDWELL, OF PHILADELPHIA, PENNSYLVANIA, ASSIGNOR TO
HARRIS C. WILKINSON AND ANDREW E. SMYTHE, OF SAME PLACE.

DESIGN FOR A MAGNETO-GALVANIC MEDAL BATTERY.

SPECIFICATION forming part of Design No. 11,637, dated February 3, 1880.
Application filed December 29, 1879. Term of patent 7 years.

To all whom it may concern:

Be it known that I, EDWARD P. CALDWELL, of the city and county of Philadelphia, and State of Pennsylvania, have invented and produced a new and original Design for a Magneto-Galvanic Battery, of which the following is a full, clear, and exact description, reference being had to the accompanying drawing, making part of this specification.

10 In the said drawing, *a b* represent two concentric rings, between which are arranged a series of small disks, *c*, the peripheries of which are in contact with each other and with the rings *a b*. Within the inner ring, *b*, is placed 15 a heart-shaped center-piece, *d*, and outside the ring *a* is placed a rim, *e*, of magnetized iron, the ends of which are separated, leaving a space, *f*, between them, the whole forming a unique and ornamental design.

The heart-shaped center-piece or the whole 20 or any portion of the battery may be ornamented with figures or devices of any desired description.

What I claim as my invention, and desire to secure by Letters Patent, is—

25 The design for a magneto-galvanic battery, consisting of the heart-shaped center-piece *d*, surrounded by the concentric rings *a b* and outer rim, *e*, and the disks *c*, arranged within the space between the rings *a b*, all substantially as herein shown and described.

30 Witness my hand this 24th day of December, A. D. 1879.

EDWARD P. CALDWELL.

In presence of—
J. M. DOWNING,
M. M. BUXTON.
